UNITED STATES PATENT OFFICE.

EDWIN V. HAGMAN, OF BOSTON, MASSACHUSETTS, ASSIGNOR TO ALFRED A. ZIEGLER,
TRUSTEE, OF BOSTON, MASSACHUSETTS.

APPARATUS FOR SENDING AND RECEIVING INFORMATION.

1,276,350.

Specification of Letters Patent. Patented Aug. 20, 1918.

Application filed May 13, 1914. Serial No. 838,254.

To all whom it may concern:

Be it known that I, EDWIN V. HAGMAN, a citizen of the United States, residing at Boston, in the county of Suffolk and State 5 of Massachusetts, have invented an Improvement in Apparatus for Sending and Receiving Information, of which the following is a specification.

This invention relates to apparatus for 10 communicating definite information from one point to another by electro-mechanical means. It is especially desirable for transmitting ranges from a bridge, conning-tower, or other station on a war vessel to the various gun-stations, and will be herein-after described in that connection, although its scope is not limited thereto. With slight 15 variations the apparatus, hereinafter to be described, may be used for transmitting deflections.

By my invention, the range (in yards) or the deflection (in knots) can be quickly, accurately, and automatically sent to the gun-stations and return-signals received at the 20 sending-station to indicate the fact that the ranges or deflections have been received at the gun-stations.

The range-transmitter or it may be the deflection-transmitter, is employed at the 25 sending station having circuit-controlling means by which to control the operation of a register at a gun-station, said transmitter having hand-actuators for the circuit-controlling means, one for sending the ranges, 30 say from 0 to 950, in increments of 50, and the other for sending ranges, say from 1000 to 19000 inclusive, in increments of a 1000, either one or both being employed as occasion demands. One of the hand-actuators 35 may be arranged at one end of the instrument for operation by the right hand and the other may be arranged at the other end of the instrument for operation by the left hand, although such arrangement is not material. A motor is provided at the gun-station of receiving-station which is associated with the register, by which the register 40 is operated to set up different numbers, as for instance, by rotarily moving number-drums on the peripheries of which the numbers are arranged. The motor is of the rotary type and arranged for operation in either direction and the register is also of the rotary type and arranged for operation 45 in either direction, so that when setting up

a number, the motor and register may be moved rotarily through the shortest arc to arrive at the number to be set up on the register, thus saving much time. The number-drums of the register are arranged for 50 movement by a mechanical connection with the motor shaft.

Numerous controlling devices are provided for the transmitter, some of which are arranged for operation by means associated 55 with the motor, and others by means associated with the register, and others by component parts of the transmitter, and said controlling-devices are so arranged as to cause all movements of the apparatus to be 60 performed in a prearranged order, for the correct sending and receiving of the signals, otherwise the signal will not be sent, or if sent, the fact will be made known that it 65 was not received.

In the accompanying drawings, Figure 1 is a plan view of the exterior of the range-transmitter.

Fig. 2 is a sectional front elevation of the transmitter with the front of the casing removed.

Fig. 39 is a sectional detail to be referred to.

40 Figs. 40 and 41 are fragmentary details to be referred to.

Fig. 42 is a fragmentary detail of a portion of the motor.

The component parts of the range-register, see Figs. 21 to 31, are arranged in a case 200, having an opening or window 201, at the top, through which the range-numbers are visible. The right hand or unit-number 202, is zero and is mounted on

50 a stationary member or dummy. The "tens" numbers are carried by a movable target 203, which has arranged thereon two numbers only, viz:—0 and 5, because the variations in the range-numbers are, for

55 convenience, by increments of fifty, and one or the other will therefore be brought into visible position by a movement of the target. A similar target 204 is arranged for the "tens of thousands" numbers, which

60 has arranged thereon two numbers only, viz:—0 and 1, as the range-numbers will not ordinarily reach 20,000, and one or the other number will be brought into visible position by a movement of the target. The

65 "hundreds" numbers are arranged on the

periphery of a rotary-drum 205, loosely mounted on a shaft 206, and the "thousands" numbers are arranged on the periphery of a rotary drum 207, also loosely mounted on said shaft 206, and each of said drums has numbers ranging from 0 to 9. By this arrangement any number from 00000 to 19950, varying by increments of fifties, can be brought into visible position.

The numbers on the number-drums 205 and 207 are equi-distantly disposed throughout their entire circumferences, and hence they are each designed to be moved into ten predetermined positions to bring their different numbers into visible position. To rotate said drums each drum has fixed to it a toothed gear, as 208, 209, and said gears respectively engage toothed driving-gears 210, 211, the gear 210 being secured to the inner end of a sleeve 212, and the gear 211 being secured to the inner end of a sleeve 213, and said sleeve being arranged in alignment and both supported loosely on a shaft 214 and spaced apart. They are thus free to revolve on said shaft as a bearing.

It is herein designed to employ said shaft 214 as the driving-shaft for both drums, and to employ a single motor for rotating it. Therefore means are provided for clutching the driving-gears 210 and 211, or otherwise separately connecting them with said shaft.

Referring particularly to Figs. 22 and 29 to 31, a clutch-sleeve 215 is slidably mounted on and keyed to the shaft 214, which sleeve is movable axially by a clutch-lever 216, engaging a collar 217, on said sleeve in usual manner, said lever being fulcrumed at 216'. The clutch-sleeve or member 215 has on one side of it a projection 218, arranged to enter a hole 219, in the gear 210, thereby to connect the clutch-member with said gear, and said projection bears a roller 220 for engagement with the face of said gear 210, in case said gear is not disposed with its hole 219, in register with the projection 218, at the moment the clutch-member is moved toward the gear for engagement therewith, thus permitting free rotary movement of the clutch-member with the shaft until engagement is effected. The clutch-sleeve has on the other side of it a like projection 221, arranged to enter a hole 222 in the gear 211, thereby to connect the clutch-member with said gear, and said projection bears a roller 223 for engagement with the face of the gear 211, in case said gear is not disposed with its hole 222, in register with the projection 221, at the moment the clutch-member is moved toward the gear for engagement therewith, thus permitting free rotary movement of the clutch-member with the shaft until engagement is effected.

The holes 219 and 222 are here shown as arranged on the driving-gears 130

at places whereby said gears hold the number-drums with their zero numbers exposed to view, but they may be otherwise arranged, so far as their relation to any predetermined number is concerned, but it is of the greatest importance that they shall be arranged alike, so that they will be oppositely disposed when the same numbers are in exposed position. In view of the liability of movement of said number-drums from the position in which they may be set, by the rotation of the driving-shaft, locking-means are provided for engagement with the driving-gears, thus to hold them in different predetermined positions, and such means, as here shown, consists of a horizontally arranged bar 224, pivoted at a point 224' intermediate its length to the clutch-lever 216, and having pivotally connected to it at each end an upright lever 225, 226, said levers being pivotally connected at points between their ends at 227 to a stationary bar 227', and their upper ends arranged for engagement with any one of a plurality of pairs of projections 228, arranged on the sides of the driving-gears, there being as many pairs of projections as there are numbers on the drums and arranged at the proper places, so that when either locking-lever is in engagement with any pair of projections, a number corresponding to the location thereof will be exposed to view.

A spring 229 is connected at one end to one of the locking-levers and at the other end to a fixed point which acts to move both locking-levers and also the clutch-lever in a direction toward the left, Fig. 22, thereby to move the clutch into engagement with the driving-gear 210, and the locking-lever 225 out of engagement with said driving-gear 210 and the locking-lever 226 into engagement with the driving-gear 211, but it will be understood that the spring may be otherwise arranged to thus move all of said levers, the object being to employ a spring to impart a movement to all of said levers in one direction, and to employ other means, as will be hereinafter described, for imparting movement to them in the other direction. When said levers occupy the positions thus shown and described they are in their normal positions and the number-drum 205 is connected with the driving-shaft through the driving-gear 210, and said driving-gear is unlocked and free to be rotated, and the number-drum 207 is disconnected from the driving-shaft, (its driving-gear 211 being disconnected from said shaft,) and said driving-gear is locked in position, so that it will be held against rotation or tendency to rotate by rotation of the driving-shaft on which it is mounted. Upon movement of the clutch-lever in a direction toward the right, Fig. 22, first the clutch-member is dis-

engaged from the driving-gear 210, and is moved against or into engagement with the driving-gear 211, and the locking-levers are also moved in the same direction and in the following manner:—that is to say, when the clutch-member has disengaged the driving-gear 210, both driving-gears are then disconnected from the driving-shaft, and both locking-levers are in engagement with the respective driving-gears, the lever 225 having been moved far enough to engage the driving-gear 210, and the lever 226 having been correspondingly moved yet still remaining in engagement with the driving-gear 211, so that when the clutch is in its middle position both driving-gears are positively held by their locking-levers; then upon further movement of the locking-levers in the same direction the locking-lever 225 is moved into further engagement with the driving-gear 210 and the locking-lever 226 is moved out of engagement with the driving-gear 211.

The return movement of all said levers from the positions into which they have thus been moved to their normal positions is in a like manner, and it will be noticed that during such return movement both driving-gears are locked by the locking-levers while the clutch-member is in its middle position and is disengaged from both driving-gears. The middle position of the clutch-member when moved in either direction is utilized for it will be seen that in case the driving-gears are so relatively disposed that their holes 219 and 222 are not directly opposite each other, then the clutch-member when moving out of engagement with a hole in either driving-gear will move up to and against the face of the other driving-gear, which is its middle position, and will remain in continuous engagement with the face of said driving-gear while and during the time it is being rotated by the driving-shaft and until it has been turned far enough to permit one of its projections to enter the hole in the driving-gear against the face of which it is for the moment being held. Further reasons for this arrangement will be herein-after described.

Movement of the clutch and also of the locking-levers is arranged to be controlled from the sending-station, and, as here shown, a relay 230 is associated with the register, the armature 231 of which is connected by a spring 232, or other means, with one of the locking-levers, as 226 for instance, and said relay is normally deenergized, and when energized and its armature attracted the spring 232 will be extended and the locking-lever moved on its pivot, and, as said lever is connected with the other locking-lever and also with the clutch-lever, all of said levers will be moved at the same time by said relay.

The motor which is employed for driving

the shaft 214, is or may be the same as shown and described in my application Serial No. 838,255 filed May 13, 1914.

Referring to Figs. 32 to 35 and 37 to 42 wherein the motor is illustrated, 38 represents a toothed-gear arranged in front of and in engagement with a toothed-gear 38', on the driving-shaft 214 of the register and said toothed-gear 38 is secured to the motor-shaft 20, which shaft is rotatably mounted and is free to rotate in both directions, thereby to rotate the driving-shaft 214 in either direction and correspondingly rotate the number-drums. It is a distinct advantage to provide a motor having the capability of rotating its shaft in either direction as it enables the number-drums to be rotated in either direction, whereby they may be moved to different predetermined positions through the shortest arc, as contrasted to being moved always in a forward direction and thereby consuming a large amount of time in moving through a long arc. To accomplish this result a crescent-shaped armature 36 is secured to a support 30 arranged on the motor-shaft, and said support is also made to serve as a counterbalance for said armature, whereby said armature will have a tendency to remain in whatever position it may be set. A plurality of electro-magnets are arranged circumferentially about the motor-shaft, and are equidistantly disposed, ten such magnets being here shown, which are designated by the numerals 0, 1, 2, 3, 4, 5, 6, 7, 8, 9, and the end-portions of the cores of said magnets at one end thereof, are made to serve as the pole-pieces of the magnets. The crescent-shaped armature is here shown as arranged to enter the fields of all of the magnets, so as to be influenced by any one of them that may be energized, and will be moved upon energization of any of said magnets to bring its middle or thickest portion into the field of the energized magnet, thus to rotate the motor-shaft and in turn rotate the driving-shaft 214 of the register and correspondingly rotate one or the other number-drum according to the position of the clutch-member. These ten magnets are separately energizable by circuit-controlling means arranged at the sending-station, thereby to move the armature and rotate one or the other number-drum according to which drum is connected with its driving-shaft. Instead of employing a separate circuit-wire for each magnet in addition to a common return-wire for the purpose of separately energizing said magnets I propose to divide the magnets into two groups of five each, as for instance, to include magnets 0 to 4 in one group and magnets 5 to 9 in the other group, (see Fig. 36) and to employ two common return wires 120 and 141 and to associate therewith circuit-controlling means by which said groups are separately connect-

ed with said common return-wires 120 and 141, which enables the employment of but five circuit-wires as 121 in addition to said two common return-wires, said five circuit-wires each being arranged for connection with two of the magnets of each group, and circuit-controlling means are provided at the sending-station for controlling the connections of said common return-wires with any of said five circuit-wires, which circuit-controlling means is in addition to the circuit-controlling means for said five circuit-wires. The circuit-controlling means for the two groups of magnets, which are associated with the magnets, are arranged to be operated by means controlled by the magnets, and, as here shown, at the heel-end of each magnet (see Fig. 33) is an auxiliary-armature 44, which is pivoted at 46, and movable toward and from the corresponding end of the core of the magnet, but normally held retracted by a spring 50, connected to a ring 50^a attached by studs 50^b to the plate 22, said end of the core being enlarged to enlarge the field by arranging an iron nut 47 thereon, which latter also serves to hold the parts of the magnet assembled, and in engagement with its supporting-plate. Each auxiliary-armature 44 has a tail-piece 48, which extends inward radially toward the motor-shaft 20, and the tail-pieces 48 of the auxiliary armatures of one group of magnets coöperate with beveled-teeth 52, on a carrier 54, see Figs. 38 and 40, which for convenience is loosely mounted on the motor-shaft 20, in a recessed portion of the plate 22, and the tail-pieces 48 of the auxiliary armatures of the other group coöperate with similar beveled-teeth 56, on a carrier 58, see Figs. 38 and 41, also for convenience loosely mounted on said shaft 20, in the recessed portion of said plate 22. The teeth 52 and 56 are formed respectively as sectors, and said sectors are arranged on their carriers and relative to each other, so that their teeth form a circular series, and the beveled faces of the teeth extend diagonally across the faces of the carriers. The movement of any auxiliary-armature 44 into attracted position causes its tail-piece 48, to engage the beveled side of one of the teeth 52 or 56, and thus to impart a slight rotary motion to the carrier 54, or 58, the carrier subsequently returning to normal position upon retraction of the auxiliary armature and a corresponding movement of its tail-piece. The carrier 54 has a contact-strip 60 arranged radially on a block 61 of insulating material, which is of sufficient length to engage five contact-fingers 62, 62^a, 62^b, 62^c, 62^d, which are arranged in parallel relation and mounted on a block 63 of insulating material attached to the end wall 22, and each of said fingers is connected by a conductor 64, to a stationary conducting-strip 65 attached to 13

a block 66 of insulating material, arranged on the end-wall 22, and each of said strips 65 is connected by a conductor 67, with one of the magnet-coils 5, 6, 7, 8, 9. Thus it will be observed that the contact-carrier 54, controls the circuits to all of the electro-magnets in the lower half of the series. A spring 69 is connected at one end to the carrier 54, its other end being connected to an ear 10 on the plate 22, and tends normally to hold the contact-strip 60 in engagement with the fingers and to return said strip to such engaging-position upon retraction of the auxiliary-armature. The carrier 58 has a contact-strip 70 arranged radially on a block 71 of insulating material, which is of sufficient length to engage five contact-fingers 72, 72^a, 72^b, 72^c, 72^d, which are arranged in parallel relation and mounted on a block 74 of insulating material, attached to the plate 22, and each of said fingers is connected by a conductor 76, to a stationary conducting-strip 75, attached to a block 77 of insulating material, arranged on the end-roll 22, and each of said strips 75 is connected by a conductor 78, with one of the magnet-coils 0, 1, 2, 3, 4. Thus it will be observed that the contact-carrier 58 controls the circuits of all of the electro-magnets in the upper half of the series. A spring 79 is connected at one end of the carrier 58, and its other end is connected to an ear 80, which projects inwardly from the plate 22. This spring tends normally to hold the contact-strip 70, in engagement with the fingers 72, and to return said strip to said engaging-position upon retraction of the auxiliary-armatures. For the purpose of locking the main-armature 36, when it arrives at a predetermined position and to hold it in such position until again moved, a disk 82 is secured to the shaft 20 which has notches 84 in its periphery, equi-distantly disposed, and corresponding in number to the number of electro-magnets, and a pawl 88 which is arranged to engage of said notches. Said pawl 88 is pivoted at 90 and is engaged by a leaf-spring 91, which tends to hold its tooth 86 in engagement with the notches 84, and said pawl has a cam 92, adapted to be engaged by a pin 93, which projects from the carrier 54, and by a pin 94, which projects from the carrier 58. Either of said pins operates to raise the pawl 88, and withdraw its tooth 86, from the notch 84, in which it has been engaged, when the carrier bearing it is given a slight rotary motion by a tail-piece 48, thereby unlocking the shaft 20, so that the armature 36 may be rotated under the influence of any of the electro-magnets.

When a tail-piece 48, is swung outwardly, by attraction of an auxiliary-armature, and engages the teeth 52 or 56, according to which magnet is energized, and slightly ro-

tates the corresponding carrier 54 or 58, the shaft 20, will be unlocked, and will remain unlocked until the tail-piece is swung inwardly by the retraction of the auxiliary-armature upon deenergization of the magnet. Thus the locking of the motor-shaft and main-armature is controlled by the auxiliary-armature, through the members 54 and 58, and pins 93 and 94 borne by said members, and it will be observed that this function of said members is quite independent of their circuit-controlling function. 75

A pair of pawls 95, 96, are pivotally supported on a plate 99 connected with the member 82, and are yieldingly held against a stop 97 by a spring 98, which is connected to both of said pawls. When these pawls approach the tail-piece of the auxiliary-armature of an energized magnet the first pawl which encounters the tail-piece is 85 swung outward to allow said tail-piece to enter between the two pawls and to engage the second pawl, thereby to suddenly arrest said member 82 and shaft 20 against rotation. When the magnet is deenergized and 90 its auxiliary-armature retracts, its tail-piece resumes its normal position and disengages said arresting pawls 95 and 96.

Terminal plates are arranged on the outside of the casing 24, see Figs. 36 and 37, to 95 which the circuit-wires from the sending station are connected, and, as here shown 100, and 101, represent two end terminal plates of the two sets of magnets, which are mounted respectively on blocks 108, 117, of insulation attached respectively to the two halves of the casing 24, and 102, 103, 104, 105 and 106 other terminal plates attached to the block 108, which are connected respectively to other terminal plates 112, 113, 114, 115, 105 116, attached to the block 117, see Fig. 42.

As here illustrated (see Fig. 36), the terminal-plate 100, is connected by a wire 120 to one side of magnet 0, and the other side of said magnet is connected by a wire 121 110 to the terminal 102. One side of the magnets 0 to 4 are connected by wires 122, 123, 124, 125 and 126 to the contact-fingers 72, 72^a, 72^b, 72^c and 72^d, respectively, and one side of magnets 5 to 9 are connected by wires 127, 128, 129, 130, 131, to contact-fingers 62, 62^a, 62^b, 62^c and 62^d, respectively. The other side of said magnets 5 to 9 are connected by wires 132, 133, 134, 135 and 136 to magnets 0 to 4, respectively, and the magnets 1 120 to 4 and 9 are connected by wires 137, 138, 139, 140 and 141 to the terminals 103, 104, 105, 106 and 101, respectively.

The operation of this group of mechanism is as follows:—

Suppose that the circuit is closed between the terminal-plates 100 and 104, by means of any suitable circuit-closing device connected with a source of current. The current will flow from the terminal 100, through 130

wires 120, 122, finger 72, bar 70, finger 72^b, wire 124, magnet 2, wire 138 to terminal 104, thus energizing the coil 2. The first result of this energization will be to attract 5 the auxiliary-armature 44 of this magnet, and swing outward the tail-piece 48, the latter engaging the teeth 52 and rotating the carrier 54, slightly to cause the pin 93 to engage the locking-pawl cam 92, and move 10 the locking-tooth 86 to disengage the disk 82. The shaft 20, is now unlocked, and the main-armature 36 moves rotarily to bring its thickest portion into the field of magnet 2. In the meantime, as soon as the tail-piece 15 has effected the unlocking of the shaft 20 and the latter rotated, the former enters the gap between the two arresting-pawls 95, 96, and arrests said shaft; also the rotary motion imparted to the carrier 54 causes the 20 contact-bar 60 to disengage the contact-fingers 62, 62^a, 62^b, 62^c, 62^d, to break the circuit through the lower set of magnets to prevent energization of any of the magnets of said set. When the magnet 2 is deenergized 25 the carrier 54 is returned by the spring 69 and the strip 60 again engages the fingers 62, 62^a, 62^b, 62^c, 62^d, and the disk 82 and shaft 20, together with the main-armature 36 remain locked until another magnet 30 is energized, whereupon its auxiliary-armature operates as above described. In case the shaft 20 was locked by a previous operation of magnet 3, and the thickest part of the armature 36 is in the field of said magnet 3 35 at the time magnet 2 was energized, it will be observed that the shaft 20 will be rotated backward, such being the shortest rotary movement, to bring the thickest part of the armature into the field of magnet 2; or in 40 case the shaft 20 was locked by a previous operation of magnet 1, at the time magnet 2 was energized, then the shaft 20 will be rotated forward.

In this diagram the magnet coils 0 to 4 45 of one set are electrically connected by wires 132 to 136 to the magnet coils 5 to 9 of the other set, instead of the terminal plates 102 to 106 directly engaging the terminal-plates 112 to 116, as represented in Fig. 42. By 50 this arrangement of circuits it will be observed that the terminal-plate 100 and wire 120 leading from it are common to all of the magnet-coils 0 to 4 of one set, as said wire 120 leads to the coil 0, and the wire 78 leads 55 from said coil to the set of contact-fingers 72 to 72^d, which are normally closed by the contact-strip 70; and that the terminal-plate 101 and the wire 141 leading from it are common to all of the magnet-coils 5 to 9 of the other set, as said wire 141 leads 60 to the coil 9, and a wire 131 leads from said coil to the set of contact-fingers 62 and 62^d, which are normally closed by the conducting-strip 60 and that separate wires also lead 65 from said magnet-coils 0 to 4 to one set of

contact-fingers 72 to 72^d, and that separate wires also lead from said magnet-coils 5 to 9 to the other set of contact-fingers 62 to 62^d. The common wires 120 and 141 are shown in diagram as leading to the magnet-coils 0 to 9 for convenience instead of extending directly to the conducting-strips 70 and 60, respectively.

At the sending-station is arranged the circuit-controlling means for the magnets 0 to 9 of the motor, whereby the number-drums of the register are rotarily moved into different position, said circuit-controlling means having associated therewith graduated scales by which their positions are indicated to predetermine the operation of the motor and the corresponding operation of the register associated therewith. The instrument involving this means is represented in Figs. 1 to 20. The component parts of this instrument are mounted on a base 400, and inclosed in a case 401. The range-numbers are arranged in two rows 402, 403, see Fig. 1 which correspond to the numbers on the two number-drums 90 and in addition thereto to the numbers on two targets, one for the fifties and the other for the tens of thousands. All of these numbers are arranged on a plate beneath an opening in the case. Adjacent each row 95 a slot is formed in which slot pointers 404, 405 are movable to point to the various numbers.

The row 402, here termed the "hundreds" scale consists of the numbers 0 to 950, in increments of fifty, and the row 403 here termed the "thousands" scale consists of the numbers 0 to 19 inclusive. The pointer 404 is designed to be moved along the slot by a hand-actuator 406, here represented as located at the right hand of the instrument, and the pointer 405 is designed to be similarly operated by a hand-actuator 407, here represented as located at the left hand end of the instrument. The pointer 404 is secured to a block 408, internally screw-threaded and arranged for movement on and by a worm-shaft 409, and said shaft is mounted for rotation in suitable bearings and has secured to it at one end a pinion 410, see Fig. 5, which is engaged and driven by a train of gearing engaging a beveled pinion 411, which is secured to a shaft bearing a toothed gear 412, which is engaged and driven by another train of gearing engaging a toothed gear 413, (see Fig. 6), which is secured to the lower end of an upright sleeve 414, having suitable bearings, the upper end of said sleeve being secured to an upright sleeve 415, having suitable 110 bearings, and said sleeve 415 being rigidly connected with the hand-piece 406. By swinging said hand-piece 406 in an arc of a circle said sleeves and trains of gearing are moved and the worm-shaft is rotated, 115 120 125 130

The trains of gearing are especially provided for the purpose of enabling the hand-piece to be moved through a short arc and the worm-shaft to make a complete rotation 5 for each number indicated on the scale, thus to move the pointer the entire length of the slot to point to all of the numbers in the row. Said block 408 carries the movable contact-members of one group of circuit-controlling means for the motor, and, as here shown (see Figs. 3 and 10), has attached to it a block 417 of insulation, to which two pairs of contact-members are attached, said members being represented at 10 418 and 419, and one of said pairs of contact-members, as 418, is arranged for engagement with stationary contact-members 420 and 421, secured to a block 423 of insulation which is extended the entire length 15 of the row of numbers, there being one contact-member 420 common to all of the contact-members 421 (see Fig. 11), and there being ten of said contact-members 421, which correspond to the ten magnets of the 20 motor; and the other pair of contact-members, as 419, being arranged for engagement with the stationary contact-members 424, 425, 425^a, also secured to said block 423, there being one contact-member 424, common to the contact-members 425 and 425^a, and said contact-members 425, and 425^a correspond to the two groups of magnets of the 25 motor. As the block 408 is moved along by the hand-piece, the contact-members borne 30 by it are correspondingly moved over the stationary contact-members, and the pair of contact-members 418 and their coöperating stationary contact-members 420 and 421 are arranged for connection with the separate 35 magnets 0 to 9 of the motor, when the motor is arranged in connection with the "hundreds" number-drum, and the pair of contact-members 419 and their coöperating stationary contact-members 424, 425 and 40 425^a, are arranged for connection with two common return-wires which are connected with the group-selecting circuit-controller at the motor, by which selection of one or the other group of magnets 0 to 4 and 5 to 9 45 50 is accomplished.

Referring to Fig. 11, it will be observed that the stationary contact-member 425, is coextensive with the first group of five stationary contact-members 421, and that the 55 stationary contact-member 425^a is coextensive with the second group of five stationary contact-members 421, and by this arrangement while the movable contact-member 418 is in engagement with any one 60 of the five stationary contact-members of the first group the movable contact-member 419 is in engagement with the stationary contact-member 425, and while the movable contact-member 418 is in engagement with 65 any one of the five stationary contact-mem- bers of the second group, the movable contact-member 419 is in engagement with the stationary contact-member 425^a, thus to make electrical connections with the separate groups of magnets of the motor and 70 the separate magnets of said groups. The pointer 405 is secured to a block 426, which is internally screw-threaded and arranged for movement on and by a worm-shaft 427, and said shaft is mounted for rotation in 75 suitable bearings and has secured to it at one end a pinion 428, see Fig. 4, which is engaged and driven by a train of gearing engaging a bevel-pinion 429, which is secured to a shaft bearing a toothed-gear 430, which is engaged and driven by another train of 80 gearing engaging a toothed-gear 431, which is secured to the lower end of a sleeve 432, having suitable bearings, the upper end of said sleeve being secured to a sleeve 433, 85 having suitable bearings, and said sleeve 433 being rigidly connected with the hand-piece 407. By swinging said hand-piece 407, in the arc of a circle, said sleeves and trains of gearing are moved and the worm-shaft is rotated in a manner similar to the 90 corresponding parts connected with the hand-piece 406. Said block 426 carries the movable contact members of the other group of circuit-controlling means for the motor, 95 and as here shown, has attached to it a block 434 of insulation to which two pairs of contact-members, as 435, 436, are attached, one of said pairs of contact-members, as 435, being arranged for engagement 100 with stationary contact-members 437, 438, secured to the other side of said block 423 of insulation, there being one contact-member 438, common to all the contact-members 437, and there being, as here 105 shown, twenty contact-members 438, the first ten corresponding to the ten magnets of the motor and the second ten being a duplication of the first ten, and the other pair of contact-members, as 436 being arranged for engagement with stationary contact-members 439, 440, 440^a, also secured to said block 423, there being one contact-member 439, common to all the contact-members 440 and 440^a, and there being here shown 110 two groups of contact-members 440, 440^a, the first group corresponding to the two groups of magnets of the motor, and the second group being a duplication of the first group, so that as the block 426 is moved 115 along by the hand-piece 407, the contact-members borne by it are correspondingly moved over the stationary contact-members. The pair of contact-members 435 and their coöperating contact-members 437, 438, are 120 arranged for connection with the separate magnets 0 to 9 of the motor when the motor is arranged in connection with the "thousands" number-drum, and the pair of contact-members 436 and their coöperating con- 125

65 70 75 80 85 90 95 100 105 110 115 120 125 130

5 tact-members 439, 440 and 440^a, are arranged for connection with the two common return-wires which are connected with the group-selecting circuit-controller at the 10 motor by which the selection of one or the other group is effected. Referring to Fig. 12 it will be observed that the contact-members 440, 440, are coextensive with the first and third group of five contact-members 15 437, said contact-members 440, 440, being connected with the common return-wire of one group of magnets of the motor, and the first and third groups of contact-members 437 being connected with the five magnets 20 of said group; and that the contact-members 440^a, 440^a, are coextensive with the second and fourth group of five contact-members 437, said contact-members 440^a, 440^a, being connected with the common return-wire of 25 the other group of magnets of the motor, and the second and fourth group of contact-members 437 being connected with the five magnets of said group, so that while the movable contact-member 435, is in engagement with any contact-members of the first and third groups the movable contact-member 436, is in engagement with the contact-members 440, 440, corresponding to said first and third groups of contact-members; 30 and while the movable contact-member 435 is in engagement with the contact-members of the second and fourth groups, the movable contact-member 436 is in engagement with the contact-members 440^a, 440^a, corresponding to said second and fourth groups of contact-members 35 437, thus to make electric connections with the separate group of magnets of the motor and the separate magnets of said groups.

40 It will be observed that on the "thousands" scale are numbers 0 to 9 representing the thousands, and also numbers 10 to 19 representing the tens of thousands, and the thousands are indicated on the "thousands" number-drum with the target 204, set at 0, and the tens of thousands are indicated on the same drum with the target 204 set at 1, and the two groups of circuit-controlling means here shown in duplicate, see Fig. 12, 45 are employed for controlling the motor while the "thousands" number-drum is in operative connection therewith, the first group being employed to operate the motor and consequently the number-drum to indicate 50 the thousands and the second group, which is a duplicate of the first group, being employed to operate the motor and consequently the same number-drum to indicate the tens of thousands.

55 It will be remembered that the clutch for the number-drums is normally in position either connecting or to connect the "hundreds" number-drum with its driving-shaft, and hence with the motor, and that 60 65 said clutch must be shifted to connect the

"thousands" number-drum with said driving-shaft and motor, and that such shifting of the clutch is accomplished by means of the relay 230, which is associated with the register, so that, when sending a range number of less than a thousand the clutch need not be operated by the relay, but when sending a range number of a thousand or greater said clutch must be shifted, and hence means are associated with the "thousands" actuator 70 407, only, for thus causing clutch-operating relay 230 to shift the clutch. Also said means must be operated to control said relay before the "thousands" actuator is rotated, and, as here shown, see Fig. 4, a circuit-controller is provided for the circuit of said relay 230, represented by a pair of stationary contact-members 445, 446, and a movable contact-member 447. The stationary contact-members 445, 446 are arranged on a 80 block 448, of insulation, and the movable contact-member 447 is arranged on a block 449 of insulation, and said block 449, is connected with means by which it is moved up and down by means associated with the 85 "thousands" hand-actuator 407. It so happens that said block 449 carries other contact-members, which will be referred to, and also said block and the means for moving it are associated with the "thousands" actuator 90 407, in the same manner as a corresponding block bearing contact-members is associated with the "hundreds" hand-actuator 406, and reference is therefore now made to Fig. 6, wherein the "hundreds" 95 actuator is shown. The moving-means for the block involves a sleeve 450, to which said block is attached, which sleeve is loosely mounted on a stem 451, and rests on a collar 452 on said stem, and said stem is movable 100 axially for a short distance and extends up through the sleeve 414 and terminates in a chamber in the hand-piece of the actuator, wherein means are provided for lifting it, thereby to lift the block 449 against the 105 stress of a return-spring 453. The means here shown for moving said block consists of a lever 455, arranged within the hand-piece and pivotally supported, and engaging, at one end, the upper end-portion of said 110 stem, its other end extending beneath a thumb-piece 456, by which said lever is depressed, and also another lever 457, pivotally supported within the hand-piece, one end of which engages the aforesaid lever 115 455, and the other end extends beneath a finger-piece 458, seated in the hand-piece, which when depressed acts to move it. By pressing inward either or both pieces 456, 458, the stem will be lifted thereby raising the 120 block and causing the contact-member 447, to engage the contact-members 445 and 446, and close the circuit of the relay 230.

125 It is very desirable that the circuit-controlling means for the motor which is oper- 130

ated by the hand-actuators shall be arranged to operate on an open circuit, thereby to prevent arcing, and to accomplish this result another circuit-controller is arranged in a 5 circuit-wire which is common to all the circuits which connect the motor with the groups of circuit-controlling means, and referring to Figs. 2, 9, 14 and 22, 460 and 461 represent a pair of stationary contact-members 10 arranged on a block 462 of insulation, and 463 a movable contact-member arranged on the armature-lever 464 of a relay 465 which is associated with the sending instrument, said contact-members constituting the 15 circuit-controller in said common circuit-wire. The circuit of said relay 465 is controlled by both the "thousands" actuator and the "hundreds" actuator to close said common motor circuit.

20 In view of the fact that when operating the "thousands" actuator the clutch must be disengaged from the "hundreds" number-drum and that the motor-circuit must not be closed by this common circuit-controller 460, 25 461, 463, until after such disengagement has been effected, it is herein designed to operate the circuit of the relay 465, by means associated with the clutch-mechanism, which it will be understood is controlled by the "thousands" actuator only through the relay 230, 30 and, herein, as seen in Fig. 22, the clutch-lever 216 is arranged to engage a contact-member 235, which latter, when depressed, engages a contact-member 236, thereby to 35 close the circuit of said relay 465, when the relay 230 is energized and its armature is attracted, as at such moment the clutch-lever is moved and the "hundreds" number-drum is disengaged, although said clutch-lever 40 may be moved only into its middle position, preparatory to engaging the other drum. But when operating the "hundreds" actuator the clutch has disengaged the "thousands" number-drum upon deenergization of said 45 relay 230, and hence the circuit of the relay 465 may be directly controlled by a circuit-controller which is associated with the "hundreds" actuator. Referring to Figs. 5, 5^a, 6 and 36, a pair of stationary contact-members 50 466, 467 are arranged on the stationary block 448 of the "hundreds" actuator, which contact-members are adapted to be engaged by a contact-member 468, attached to the block 449 on the sleeve 450, which is adapted to be 55 raised by said sleeve to close the circuit. Thus upon lifting the sleeve of the "hundreds" actuator the circuit of said relay 465 is also closed.

The relay 465 in addition to thus controlling said common circuit-wire, also controls the operation of locking-means for the sleeves 450 associated with both hand-actuators, and upon energization of said relay 465, the locking-means are operated to 60 engage the sleeves and hold them in an ele- vated position, so as to prevent them from returning to normal, said locking-means holding the sleeves with the contact-members 466, 467 borne by them in engagement with the stationary contact-members 468, thereby 70 to maintain the circuit of said relay 465, closed at this point, although other functions are also subserved, as will be hereafter described. As here shown, in Fig. 2 particularly, said locking-means consists of a pair 75 of engaging-bars 470, 471, slidably mounted for engagement, respectively, with said sleeves, and said bars are arranged in alignment and their inner or adjacent ends are inclined and engage a pair of rolls arranged on 80 a support 472, which support is loosely connected with an arm attached to the rotating armature-carrying shaft of the relay 465, and a spring 473 is connected at its ends with both bars, tending to draw them inward 85 toward each other and into engagement with the rolls. Upon energization of said relay 465, responsive to the circuit-controller operated by the clutch-lever 216, which is controlled by the "thousands" actuator, the bar 90 470 will be moved longitudinally into engagement with the sleeve, of the "thousands" actuator, and upon energization of said relay 465, responsive to the circuit-controller associated directly with the "hundreds" actuator, 95 the bar 471 will be moved longitudinally into engagement with the sleeve on the "hundreds" actuator.

These locking-bars are subsequently operated to disengage the sleeves, as will be 100 hereinafter described. It will be noted that energization of the relay 465 also indicates the fact that the clutch has been shifted.

Upon closure of the common motor-circuit by either the "thousands" or the "hundreds" actuator thus described, involving the operation of the relay 465, the circuit of any magnet of the motor which is closed by either hand-actuator at such moment will be closed and the corresponding magnet will 105 110 be energized. When said motor-magnet is thus energized the auxiliary-armature 44 of said magnet is attracted, unlocking the armature-shaft of the motor and permitting rotary movement thereof to bring the armature into correct position with respect thereto, to admit of reengagement of the clutch which has been previously moved. The said auxiliary armature 44 is also arranged to control the circuit of a relay 480, 115 and, as here shown, said circuit is connected by wires 152', 153', see Figs. 32 and 36, with a pair of contact-members 152, 153, arranged on the outside of the end wall 22 of the motor case, and said contact-members 120 bear upon a pair of contact rings 154, 155, which are insulated from but supported by the motor-shaft 20, see Fig. 33, and said contact-rings are, respectively, connected by wires with a pair of contact-members 156, 130

157, which are arranged on an insulating disk borne by the shaft. The said contact-members 156, 157 extend upward and back of the pawls 95, 96, see Fig. 35, and their 5 extremities are normally disengaged but are adapted to be engaged to close the circuit. As here shown they are associated with the pawls and are movable with said pawls rotarily by the motor-shaft, and are brought 10 into correct position with respect to the energized magnet by the motor-shaft, in which position the pawls engage the tail-piece of the armature. An insulating pin 157² is arranged on the member 157, which extends 15 inward toward and into engagement with the pawl and also extends outward toward and into engagement with the contact-member 156, see Figs. 33 and 35, so that said contact member is movable by either pawl, and 20 will be moved when the tail-piece engages and moves either pawl. Such movement causes the contact-member 157 to move rearwardly and also causes a corresponding movement of a contact-member 156, so that both members 25 are moved but their relation to each other remains unchanged. Said contact-member 156 has arranged on it an insulating pin 156², which extends toward the tail-piece and terminates at the tail-piece when 30 the latter is in its abnormal position, with the armature attracted. This being the case, it will be observed that when the contact-member 157 is permitted to return by either pawl resuming its normal position, 35 said contact-member 156 will be held in its abnormal position by its pin engaging the tail-piece, and, as a result, the contact-member 157 will engage the contact-member 156 and close the circuit. In Fig. 35, the insulating pin 156² and the end-portion of the 40 contact-member are removed. Thus it will be seen that the circuit of the relay 480 is closed by means operated by the motor and controlled by the relay 465, and the relay 45 480 is at such time energized.

It is, however, important that the relay shall not be energized by said contact-members associated with the motor unless the clutch is in engagement with one or the 50 other number-drum, and to insure such position of the clutch, a U-shaped contact-member is associated with two contact-members 682 and 683 and the clutch-lever is extended into a position between the arms 680, 681, 55 of said U-shaped contact-member for engagement therewith and when said clutch-lever is in one or its other extreme position with the clutch in engagement with one or the other number-drum, one or the other 60 60 of said arms will be moved into engagement with one or the other contact-member and to thereby close the circuit of said relay 480, at such point. This circuit-controller operated by the clutch-lever is arranged in series relation with the aforesaid circuit-controller 65

which is associated with the motor, therefore, unless the circuit-controller which is operated by the clutch-lever is closed thereby, the operation of the other circuit-controller will have no effect. When the clutch-lever is in a middle position, both arms 680, 681, of the U-shaped contact-member are moved away from their corresponding contact-members 682, 683, so that the circuit is open at such points and is only closed when 70 the clutch-lever is in one or its other extreme position. Also in series relation in said circuit of the relay 480, is another circuit-controller, which is associated with the targets, will be hereinafter described, and not 75 until all of the circuit-controllers which are arranged in series relation in the circuit of said relay 480 are closed will said relay be energized. Referring again to Fig. 36, the circuit wire 153' extends to the terminal 80 plate 678, and wire 678' connects said plate with the U-shaped contact member 680', 681' including one or the other arm thereof and one or the other contact member 882 or 683, and a circuit wire 776 extends from said 85 contact member 882 and 683 to the circuit controller 275, 276, and a circuit wire extends from said circuit controller to the terminal 633 and circuit wire 634 connects said terminal plate with the negative side of 90 the battery. Said relay 480 is employed to control the circuit of the relay 465, for the purpose of deenergizing said relay 465, which has been previously energized, in order to open the common motor-circuit, so 95 100 that the hand-actuators may operate to move the motor circuit-controller along with the motor-circuit open, thus to avoid arcing during such movement, after which the motor-circuit is closed. This result is accomplished by providing relay-contacts 481, 105 482, arranged in the circuit of the relay 465, and engaged by a contact-roll 483, arranged on the rotary moving armature 484, of said relay 480 as seen in Fig. 10. Said relay-contacts 481, 482, are normally engaged by the contact-roll 483, when the relay 480 is deenergized, thus closing the circuit of the relay 465 at such point and at such time, but upon energization of said relay 480 by the 110 closure of its circuit by all said circuit-controllers, said relay-contacts are moved to open the circuit of said relay 465 and permit deenergization of the relay 465 and the 115 opening of the motor circuit. Another circuit-controller is arranged in the circuit of said relay 480, which consists of a pair of contact-members 485, 486, which are associated with the relay itself and arranged for engagement with the contact-roll 483 in 120 such manner that when said relay is energized and its armature attracted, said contact-roll will be moved into engagement with said contact-members 485, 486, and thereby 125 close the relay-circuit. This circuit-con- 130

troller enables the relay 480 to remain energized notwithstanding the motor-circuit has been opened and the motor-magnet has been deenergized and the auxiliary-armature 5 of the motor-magnet has returned. When first completing the motor-circuit as aforesaid, it is necessary to maintain closure thereof for a short period of time before operating the actuators, thereby to insure 10 the shifting of the clutch from one to the other number-drum, and its reengagement therewith, and to provide this interval of time, means are employed for temporarily arresting further upward movement of the 15 sleeves 450, which are associated with the hand-actuators. As here shown, a pair of bars 475, 476, are arranged for engagement with said sleeves, said bars being arranged in alinement and their inner or adjacent 20 ends connected together by a spring 477, and said inner ends of the bars are inclined, and said inclined ends engage rolls borne by a support 478, which is loosely connected with an arm 479 attached to the shaft of the 25 rotary moving armature of the relay 480. Said bars are normally in their outermost positions and designed to be drawn inward toward each other to disengage the sleeves. In this instance both bars are operated 30 simultaneously upon energization of the relay 480, to disengage the sleeves, and thus permit further upward movement of the sleeves.

To insure the circuit being normally open 35 at the sending-instrument two circuit-breakers are associated with each hand-actuator, one for each bus-bar circuit, which, when the sleeves 450 thereof are in their lowermost positions are arranged to break the circuits, 40 but which, when said sleeves are lifted, act to close the circuits at such points. As here shown, see Fig. 4, the circuit-breakers associated with the "thousands" actuator consist of a pair of contact-members 490, 491, arranged 45 for engagement with a contact-member 492, arranged in one of the bus-bar circuits, and the contact-members 499, 500 arranged for engagement with a contact-member 497, arranged in the other bus-bar circuit. As here shown, see Figs. 5 and 5^a, the 50 circuit-breakers associated with the "hundreds" actuator consist of a pair of contact-members 493, 494, arranged for engagement with the contact-member 495, and arranged 55 in one of the bus-bar circuits, and contact-members 467 and 501, for engagement with the contact-member 468, and arranged in the other bus-bar circuit. Heretofore there are described contact-members 485, 486 and 483, 60 which are associated with the relay 480, and which operate to close the circuit of said relay and thereby maintain said relay energized, but subsequently the circuit of said relay must be opened, and to accomplish this 65 result a contact-member 496 is associated with the sleeve of the "thousands" actuator and arranged for engagement with the contact-member 497, and the contact-member 498 is associated with the sleeve of the "hundreds" actuator and arranged for engagement with the contact-member 468, and upon upward movement of said sleeves the circuit-controllers thus described are closed and upon downward movement thereof are opened, thus to open the circuit of said relay 70 75 480, upon the downward movement of said sleeves.

To arrest the downward movement of the hand-actuators after they have been moved to operate the circuit-controlling device for 80 the motor, so as to afford ample time for the relay 480 to deenergize and the relay 465 to energize, a mechanical locking-device, here shown as a pawl, is provided for each actuator. Referring to Figs. 2, 14 and 15, 503 represents the pawl which is associated with the "thousands" actuator, which is pressed by a spring 504 into engagement with the sleeve of said actuator and when said sleeve is lifted said pawl moves into engaging 90 position beneath a projection 505 on the sleeve and remains in such position until positively withdrawn. The withdrawal of the pawl is accomplished by an outward sliding movement of the engaging-bar 470, 95 which, it will be remembered, is moved outward upon energization of the relay 465. 506 represents the pawl which is associated with the "hundreds" actuator, which is pressed by a spring 507, into engagement 100 with the sleeve of said actuator, and when said sleeve is lifted said pawl moves into engaging position beneath the projection 508, on the sleeve and remains in such position until positively withdrawn. The withdrawal of the pawl is accomplished by an outward sliding movement of the engaging-bar 471, which, it will be remembered, is moved outward upon a subsequent energization 105 of the relay 465. To provide against 110 upward movement of both hand-actuators at the same time a locking-device is arranged between the two actuators, which is moved by either to prevent movement of the other. Said locking-device, as here shown, see Fig. 2, consists of a long bar 510, having its end-portion arranged for engagement respectively with projections 511, 512, on the sleeves of the actuators, and said end-portions and projections are formed with beveled engaging-faces. Springs 513 and 514 are connected with said bar and extended in opposite directions which act as return springs to return the bar to its middle position. When one of the sleeves, as for instance, that one associated with the "thousands" actuator, is lifted, the bar is moved longitudinally and its opposite end-portion moved into engagement with the sleeve of the "hundreds" actuator, thereby to hold 115 120 125 130

said sleeve against upward movement, and a like operation takes place when the "hundreds" actuator is operated to hold the sleeve of the "thousands" actuator.

5 It is very desirable to know the relative positions of the sleeves and parts associated therewith of the two actuators at all times, and a visual indicator is arranged at the top of the instrument by which their position 10 may be indicated. As here shown, see Fig. 2, said indicator consists of a pointer 515, its upper end-portion being arranged for movement over a graduated dial 516, and said pointer is pivoted at 517, and its lower end-portion is arranged for continuous engagement 15 with the locking-bar 510, and as said bar moves longitudinally, the pointer is correspondingly moved. For the purpose of insuring movement of the pointer in all positions of the sleeves, said bar 510 has its bevelled end-portion made wide enough to maintain engagement with the bevel-faced projections continuously during the entire up and down movements of the sleeves. Thus 20 it will be seen that as either sleeve is moved upward and downward the indicator is correspondingly moved.

In view of the fact that the sleeves of the actuators and parts associated therewith are 25 controlled as to their movements by the relays 480 and 465, through various locking-bars heretofore described, it will be seen that said indicator also indicates the operation of said relays by indicating the positions of the 30 sleeves, and in view of the fact that said relays are controlled by means associated with the motor it will be seen that said indicator also serves as a return signal for the motor.

The target bearing the "tens" numbers 0 40 and 5, which is associated with the register, is arranged for operation by the magnet 240, and is movable into one or another of two different positions, in one position to display 0 and in the other to display 5, beneath the 45 opening in the top plate of the register. Referring to Figs. 26 to 28, the target 203 is pivotally mounted on the shaft 206, and its hub has two projections 242, 243, arranged upon opposite sides of it, and a relatively 50 large ring 241, surrounds said hub and shaft, having on its inner periphery two projections 245, 246, for engagement, respectively, with the projections 242, 243, and said ring is loosely pivoted to the armature 55 247, of the magnet 240. It is designed that upon an attractive movement of said armature the ring shall be moved downward and one of its projections will engage its corresponding projection on the target, thereby 60 to move the target in one direction from the position shown in Fig. 26 and the positions shown in Fig. 27, and upon the next attractive movement of said armature said ring shall be again moved downward and its 65 other projection will engage its correspond-

ing projection on the target, thereby to move the target in the other direction from the position shown in Fig. 27 to the position shown in Fig. 26. In order to shift the ring from one engaging-position to the other, a 70 flat spring 248, is arranged on the target, the lower end of which engages the ring, which, when the target is moved in either direction, causes a corresponding movement of the ring. Thus it will be seen that the target 75 is first moved in one direction and then in the opposite direction upon successive attractive movements of the armature. It will be noted that the spring yields to admit of the one or the other projection on the 80 ring passing by the corresponding projection on the hub of the target, upon each retracting movement of the armature.

Means are also provided for holding the target in either position it may be set, and, 85 as here shown, a pawl 249 is arranged back of the target, which is pivoted at its lower end to a fixed point, and its upper end engages the target, and a spring 250, is connected at one end to said pawl and at the 90 other end to a fixed point, said spring acting to move the pawl to one or the other side of a vertical plane and to hold it in such position. After the target is moved in either direction, the pawl is moved by it 95 and the spring acts to assist in such movement, but more particularly to hold the pawl in either position it will be moved by the target.

A block 251 is arranged on the hub of 100 the target which serves as a counterbalance therefor and also is employed by engaging the pins 252 and 253, to arrest movement of the target in both directions. The armature of the magnet 240, is counterbalanced 105 by a weight 254, see Fig. 23, arranged on an arm 255, pivoted at 256, and loosely connected with the armature.

The target 204 for the "tens thousands" numbers, and having on it the numbers 0 110 and 1, which is also associated with the register and means for moving it into its two different positions is the same as that just described, and referring to Fig. 24, 260 115 represents the operating-magnet of said target 204.

The operating-magnets 240 and 260, of the two targets, are included in separate circuits, each circuit having a circuit-controller 120 by which it is operated, and said circuit-controllers are arranged to be controlled, respectively, by the two hand actuators, as now will be described.

As here shown, there is associated with 125 the register three contact-members 261, 262, 263, arranged side by side, the contact-members 261, 263, being stationary and respectively connected by circuit-wires, 661 and 663 respectively, with the magnets 260, 240, and the contact-member 262, being movable 130

for engagement with the other contact-members 261, or 263, and connected by a circuit-wire 662 with a circuit-controller associated with the sending-instrument. Said movable contact-member 262 is adapted to be moved by the armature 231 of the magnet 230. When the armature of said magnet 230 is in retracted position said movable contact-member 262 is in engagement with the 5 contact-member 261, and the circuit of the magnet 240 is closed at such point, and when said armature is in attracted position said contact-member 262 is moved to disengage the contact-member 261, and to engage the 10 contact-member 263, thereby to close the circuit of the magnet 560 at such point. It will be remembered that the magnet 230 is employed to control the clutch for the number drums and hence may be utilized to control 15 the circuit of the operating magnets 240 and 260 for the targets. At the sending instrument the circuit-controller for the circuit connected with the common or movable contact 262, is represented by a pair of contact-members 520, 521, and said contact-members are normally open and arranged to be closed upon downward movement and also upon upward movement of means associated with either hand-actuator. Referring 20 to the hundreds hand-actuator for operating said circuit-controller, see Fig. 2, and 16 to 20, 522 represents a pivoted lever arranged for engagement with the contact-member 520, to move it into engagement 25 with the contact-member 521, and said lever has a stud 523, projecting from it, and a pivoted cam-lever 524 is arranged for movement up and down from the position shown in Fig. 16 to position shown in Fig. 17, and 30 during such movement its cam-projection will engage and pass by the stud 523, and thereby move the lever 522 to close the contact-members. A spring 525 is attached at one end to said cam-lever by which to move 35 said lever from one to its other position, and the other end of said spring is attached to the extremity of a lever 526, having a fixed pivot 527, and said lever 526 extends beyond the pivot of the cam-lever and is movable 40 from one to the other side of said pivot for purposes of moving the spring to in turn move the cam-lever. To avoid moving the cam-lever too quickly, as the spring is moved from one to the other side of the plane ex- 45 tending through the pivots, two restraining-pawls 528 are arranged on said lever 526, in position to engage with the end of the cam-lever, see particularly Fig. 19. Said pawls are normally held in a fixed position against 50 a middle pin by a spring 529, and the end of the cam-lever engages one or the other pawl, and as the lever 526 is moved the pawl which is in engagement with it remains in engagement until after said lever has been 55 thus moved, whereupon the cam-lever disen- 60 gages the pawl, and is then free to be moved by the spring. Said lever 526 is designed to be moved positively in both directions, and during each movement to operate the lever 522, to close the circuit of the operating-magnet of the target, thereby to move 65 said target from one to its other position, and to thus move said lever 526 in both directions, a gear 530 on the stem of the hand-actuator is employed, said gear actuating 70 only upon its downward movement, hence means are provided for accomplishing this result, which, as here shown, consists of a lever 531, having a fixed pivot 532, said lever being pivotally connected with the lever 526, 75 by a pivot-pin 533, and said lever has a large elongated opening at 534, through which the pivot 527 of the lever 526 extends, and said lever 531 has its opposite end arranged for engaging one or another 80 tooth of the gear 530. Also said lever 526 is extended at its inner end for engagement with one or another tooth of the gear 530. Referring to the relative position of the parts shown in Fig. 16, the gear 530 is rep- 85 90 resented in its elevated position, and one of its teeth is arranged above the lever 531, and when caused to descend, said tooth engages said lever 531, and depresses it, thereby through the pivotal connection with the lever 526, causing said lever 526 to move downward on its pivot 527, into the position shown in Fig. 17, and the cam-lever 524, to simultaneously move to move the lever 522 and close the contact-members. Such lower- 95 most position of the gear 530, it will be understood, is its normal position. The next time the gear 530 is moved upward the aforesaid actuating-levers will remain in the 100 position shown in Fig. 17, and when one of the teeth of the gear 530, is moved into position to again operate said actuating-levers, the operation is as follows:—Said tooth will engage the end of the lever 526, and thereby depress said lever and correspondingly 105 move the parts connected with it and return them to the position shown in Fig. 16, and during such movement of said parts the cam-lever again passes the stud on the lever 522 and moves said lever to again close the 110 contact-members. Thus it will be seen that the contact-members are closed upon both downward and upward movements of the cam-lever, thereby to move the target from 115 0 to 5 or from 5 to 0. In case a tooth of the gear 530 should not be brought into position above the lever which is uppermost, then, upon downward movement of said gear, said lever will enter the space between the teeth of the gear, and, as a result, 120 the actuating-levers will not be again closed and the target will remain in the position it was previously set. The circuit of the magnet 240 may be traced as follows:—(see Fig. 36): circuit-controller 520, 521, circuit- 125 130

wire 240^a, terminal 240^b, circuit-wire 240^c, terminal 240^d, circuit-wire 240^e, terminal 240^f, circuit-wire 662, contact-members 262, 261, circuit-wire 661, magnet 240, circuit-wire 240^g from the other side of said magnet which connects with circuit-wire 240^g to terminal plate 633, circuit-wire 634 to the negative side of the battery.

The circuit-wire from the sending circuit-controller to the magnet 260 is the same as aforesaid to the middle contact-member 262, and from thence extends through contact 263, circuit-wire 663, magnet 260, circuit-wire 240^g to terminal 633, and thence to the negative side of the battery.

Closing the circuit controller 520, 521, will only act to close the circuit to the target magnets at such point and not until the circuit is closed elsewhere will the target magnets become energized, as for instance, such closure may be effected by the relay 465, and, referring to Fig. 36, the circuit from the circuit controller 520, 521, to the circuit controller 800, 463, and 460 which is controlled by relay 465 may be traced as follows:—circuit controller 521, 520, circuit-wire 805, contact-member 800, controlling member 463, contact-member 460, circuit-wire 808, circuit-wire 646 to the positive terminal.

The toothed gear 530, see Fig. 7, of the "hundreds" actuator has arranged on it ten teeth 535, with spaces therebetween, and said teeth are arranged on the under side of the gear and extend downward and include approximately a half circle. This admits of the hand-actuator being moved through an arc of substantially 180° for its full travel. The teeth are disposed relative to each other, so as to successively engage the inside and outside levers 531 and 526, and when engaging the inside lever will act to move the target from 0 to 5, and when engaging the outside lever will act to move the target from 5 to 0. Said toothed gear has other teeth 536, arranged on its under side, which, when said gear is permitted to resume its normal position, will engage a fixed tooth 537 on the frame, thereby to hold it in any fixed position it may be set.

Said tooth 537 is made quite long and the spaces between the teeth 536 are approximately of a corresponding depth thus to admit of considerable vertical movement of said gear before disengagement takes place, and these teeth are utilized to prevent rotation of the hand-actuator until disengagement is effected, and such vertical movement is sufficient to insure all the successive operations to be carried on in a prearranged order up to the time when the hand-actuator can be turned. Thus the hand-actuator will be restrained from rotation until said gear has been lifted high enough to disengage the fixed tooth. Said toothed gear 530, 65 also has arranged on its upper side a pin

539, which slidably engages a hole in the driving-gear 413 which is employed to move the hundreds circuit-controller.

For operating the magnet 260 of the target 204, a like set of actuating-levers are employed, as represented in Figs. 2 and 16, with the exception of the controlling member 540, which is arranged on the stem of the "thousands" actuator, which member has two long ribs or flanges 541, 542, for engaging the ends of the actuating-levers, and one of said ribs, as 541, is arranged to move the levers to shift the target from 1 to 0 and the other rib 542 is arranged to move the levers to shift the target from 0 to 1. Said controlling-member 540, also has a series of teeth 543 on its under side for engaging a fixed tooth 544 on the frame, so that the operation of the levers by said controlling-member 540 is substantially the same as that heretofore described in connection with the controlling-member 530.

When the cam-lever 524 or the corresponding cam-lever moves the lever 522, to close the contact-members 520, 521, a spring-pressed pawl 550, acts to move into position back of a pin 551 on said lever 522, thereby to lock said lever 522 in position to hold said contact-members closed, and said lever 522 continues to remain in this position until returned by means provided for returning it. When the contact-members 520 and 521 are thus closed the operating-magnet 240 of the target 203, or the operating-magnet 260 of the target 204, is caused to operate and its armature, upon attraction through the counterbalancing lever 255, engages and moves a short arm 265, or 266, see Figs. 23 and 24, secured to a shaft 267, to turn said shaft.

A pair of contact-members 270, 271, are arranged above and in the path of movement of said short arm 265, to be engaged by said arm upon attraction of the armature of either operating-magnet, and said contact-members are normally open and are closed by said short arm to close the circuit of a relay 545, which is associated with the sending-instrument, and the armature 546 of said relay is connected with the pawl 550, and upon attraction moves said pawl to disengage the pin 551 on the lever 522, to permit said lever to return to normal position and the contact-members 520, 521, to operate and open the target-circuits.

Another pair of contact-members 275, 276, are arranged in the path of movement of said short arm 265, which are normally closed by said short arm when the armature of both operating-magnets are in their normal or retracted position, but are open when either of said armatures is attracted. These contact-members are arranged in series relation in the circuit of the relay 480, heretofore described. Also a pair of contact-members

575, 576, are arranged in the sending-instrument in series relation in the circuit of said relay 480, heretofore described, and said contact-members are arranged in the path of 5 movement of the arm 522, so that when said arm is moved to close the circuit-controller 520, 521, for either target, said circuit-controller 575, 576, will be opened but will be subsequently closed upon attraction of the 10 armature of the relay 545, thereby to close the circuit of the relay 480 at such point.

The relay 465, the two coils of which are represented in Fig. 36, as electrically connected together, is also employed to control 15 the circuit to the magnets 240 and 260, so that the circuits of said magnets will not be closed to energize the magnet until after said relay 465 has become energized and has attracted its armature and moved the circuit 20 controller 463. It will thus be observed that the relay 465 serves as a main controller for the motor and for the target controlling magnet.

The operation of sending a number will 25 now be described and the number selected will be 19,950. The "thousands" actuator, which is normally restrained from rotation, is first grasped, the stem 451 and sleeve 450 associated with it are lifted a short distance 30 into engagement with the locking-bar 475, its upward movement is checked. By the same movement the contact 447 is lifted to bridge the contacts 445 and 446, thereby closing the circuit through the clutch relay 35 230, and contact 497 is lifted to bridge contact 499 and 500, and 496, and contact 492 is lifted to close contact 490 and 491. The current will flow from the positive terminal through wire 646 to contact 445, thence 40 through contact 447 to contact 446, through wire 645 to binding-post 630, (shown in Fig. 36 as connected to the clutch relay 230 by a wire 631), then from magnet 230, through wire 632, and wire 240^a to binding-post 633, 45 which is connected by wire 634 to the negative terminal.

As previously explained the energization of relay 230 causes the swinging of clutch lever 216 to disconnect the shaft 214 from 50 the gear 210 of the hundreds drum 205. The swinging of the clutch lever 216 closes the circuit through relay 465 by depressing the contact 235 into engagement with the contact 236, and a corresponding movement 55 of the armature 231, closes the circuit of relay 260 at one point by moving the contact 262 into engagement with fixed contact 263. The circuit thus closed through the relay 465 includes the wire 646 from the positive terminal, wire 665 which connects wire 646 60 with one side of the relay 465, and a wire 666 from the other side of the relay to the contact 482. It will be remembered that the contacts 481 and 482 are normally bridged 65 by contact 483 as long as the relay 480 is de-

energized. The circuit, therefore, continues from contact 482 to movable contact 483 to contact 481, thence by wire 681 to binding-post 682, which is connected by wire 683 to contact 235; from contact 235 through contact 236 by wire 684 to binding-post 633, and thence by way of wire 634 back to the negative terminal. 70

Relay 465 being thus energized subsequent to the closing of the circuit through clutch 75 relay 230 moves the contact 463 to close the main-motor circuit controlled by contacts 460 and 461. This main-motor circuit includes wire 646 from the positive terminal to the contact 460, contact 463, contact 461, 80 wire 691, and contact 491. It will be remembered that the movable contact 492 is now bridging contacts 490 and 491. The contact 490 connects with busbar 439 by wire 690. From busbar 439 the current passes 85 through movable contact 436 of the thousands controller through the contact 440 (which controls the first group of magnets), thence through a wire 600 to the binding-post 100^b, wire 100^a, to terminal 100 of the 90 motor; thence through the wire 120 to magnet 0 of the first group; through this magnet to terminal 102, by wire 121, thence through wire 602 to the first contact in the first group 95 in the series of contacts 437; through the movable contact 435 to the busbar 438, thence by wire 638 to contact 500.

It will be remembered that contacts 499 and 500 are at this time closed by the movable contact 497. The current, therefore, 100 passes from contact 500 through contact 497 to contact 499, thence by wires 699, 700, to the negative terminal.

As previously explained the energization of magnet 0 (or any other magnet of the 105 motor) acts through the medium of the auxiliary armature and pawls 95 and 96 to close the circuit through the spring contacts 156 and 157, which are included in circuit with the contacts 152 and 153. Thus the circuit 110 through relay 480 is closed at such point. This last-mentioned circuit includes wires 646 from the positive side, a wire 680, which runs from wire 646 to one side of the magnet 480, a wire 667 to contact 576, contact 115 575, wire 675 and wire 677 which connects with wire 152' of contact 152, contact 153 and lead 153' to binding-post 678, to wire 678^a, which connects with the U-shaped contact, said U-shaped contact, to the contact 120 683, wire 776, contact 275, contact 276 which is connected by wire 240^a to binding-post 633, and wire 634, which connects with the negative side. The energization of relay 480 causes, as previously explained, the 125 movement of contact 483 to open the circuit through contacts 481, 482. As stated, the contacts 481, 482, are in the circuit of relay 465, and the energization of relay 480 thereby opens the circuit through relay 465, and 130

- as a consequence, the movable contact 463 is operated to open the main-motor circuit and the circuit of the target magnets 240 and 260; and also releases the locking-bar 475.
- 5 The locking-bar being thus released and the main-motor circuit being thus opened, the actuator of the thousands pointer 402 may be now turned, to dispose the pointer 405 over the numeral 19 and move the contact 10 435 into position to bridge the last contact 437 and busbar 438, and also move the contact 436 into position to bridge the contact 439 and 440^a. To close the main motor circuit thus established through the sending 15 instrument, the hand actuator is released, permitting the stem and sleeve 450 thereof to fall until caught by the pawl 503. Just as engagement with said pawl is effected, the circuit of the relay 480 is opened, since, 20 as previously explained, the downward movement of the sleeve 450 causes the separation of contacts 496 and 497. The opening of the circuit through relay 480 closes the circuit through relay 465 by permitting 25 the movable contact 483 to resume its normal bridging relation to the contacts 482 and 481. As previously set forth, the energization of the relay 465 is attended by a closing of the main motor circuit through 30 the contacts 460 and 461, by the movable contact 463, which is responsive to relay 465.
- The circuit thus closed through the sending instrument energizes the motor magnet 9 and causes the number drum to rotate to 35 indicate number 9 at the opening. The circuit thus closed through motor magnet 9 includes wire 646 from positive terminal, contacts 460, 463, 461, wire 691, contacts 491, 492, 490, wire 690, bus bar 439, bar 440^a 40 of the second group, wire 640^a, terminal 101^b, wire 101^a, terminal 101, wire 141, magnet 9, wire 136, to magnet 4, wire 140 from magnet 4, to terminal 106 of the motor, wire 606 and wire 606^a, to the last contact 437 of the 45 second group of this series of contacts, movable contact 435, bus bar 438, wire 638, to contact 500, contact 497, contact 499, wire 699, and wire 700, back to the negative terminal. Also during said initial downward movement of the stem and sleeve, the 50 actuating-lever for the circuit of the target magnet 240 operates to close said target-circuit and cause the target to move from 0 to 1. Means associated with said target 55 then operates to close the circuit of the relay 545 to restore the contact-members of the target-circuit. At this time 19 will appear at the opening of the register which corresponds with 19 on the "thousands" scale of 60 the sending-instrument. Also when the circuit of the relay 465 is thus again closed and the relay operates, the locking-bar 470 is moved to disengage the pawl and engage the sleeve, which acts to hold the sleeve still 65 in an elevated position while the motor is

turning the number-drum to bring number 9 into position at the opening. When the motor thus arrives in such position, the return-circuit of the relay 480 is again closed and the relay operates to open the circuit of the relay 465, and said relay 465 upon de-energization, permits movement of the locking-bar 470 to disengage the sleeve, whereupon the stem and sleeve resume their normal positions. When the stem and sleeve thus resume their normal position, the circuit of the clutch-relay is opened and the clutch-lever is moved by its actuating-spring in a direction toward the "hundreds" number-drum for engagement therewith.

The "hundreds" actuator, which is normally restrained from rotation is then grasped, and the stem and sleeve associated therewith are lifted a short distance into engagement with the locking-bar 476, directly closing the circuit of the relay 465, and then said relay closes the circuit of any one of the motor-magnets and the armature of the motor, which latter is now set at number 9, will be revolved until the clutch 90 engages the "hundreds" number-drum, and then the order of operation in a pre-arranged manner, is the same as just described in connection with the "thousands" actuator, and 950 is indicated on the "hundreds" 95 scale, and 950 is set up at the opening of the register. During these operations the clutch-relay serves to select the number-drum, said relay when energized, causing the clutch-lever to engage the "thousands" number-drum, and when deenergized, permitting the clutch to associate with, or reengage the "hundreds" number-drum.

Also during these operations, the clutch-relay is employed as the selecting-means for 105 the targets, in that, when the armature of said relay is in retracted position and the clutch engages the "hundreds" number-drum, the circuit of the "tens" target is closed at such point, and when the armature 110 of said relay is in attracted position and the clutch engages the "thousands" number-drum, the circuit of the "tens of thousands" target is closed at such point.

I claim:

1. An apparatus for sending and receiving information comprising a register at the receiving-station having two rotatable number-drums, a motor having a shaft and comprising a plurality of electro-magnets, and an armature common to all said magnets, means to separately connect the number-drums with the motor-shaft, and two sets of circuit-selecting means at the sending-station for the circuits of said electro-magnets, there being one set corresponding to each number-drum, substantially as described.

2. An apparatus for sending and receiving information comprising a register at the receiving-station having two rotatable num- 13

- ber-drums arranged for rotation in either direction, a motor having a shaft arranged for rotation in either direction and comprising a plurality of electro-magnets controlling rotation of the shaft, one for each number on said drums, means to separately connect the number-drums with said motor-shaft, and two sets of circuit-controlling means at the sending-station for the circuits of the electro-magnets of the motor, there being one set corresponding to each number-drum, substantially as described. 6. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft, one for each number on said drums, means to separately connect the number-drums with said motor-shaft, said means being normally arranged with one of the number-drums in connection with said shaft, two sets of circuit-controlling means at the sending-station for the circuits of the electro-magnets of the motor, there being one set corresponding to each drum, two hand-actuators, one for each set of circuit-controlling means and means associated with one of said hand-actuators by which to move said connecting-means to disengage one of the number-drums and engage the other drum, substantially as described. 7. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft, one for each number on said drums, means to separately connect the number-drums with said motor-shaft, two sets of circuit-controlling means at the sending-station for the circuits of the electro-magnets of the motor, there being one set corresponding to each drum, two hand-actuators, one for each set of circuit-controlling means and means associated with one of said hand-actuators by which to move said connecting-means to disengage one of the number-drums and engage the other drum, substantially as described. 8. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft, one for each number on said drum, two sets of circuit-controlling means at the sending-station for the circuits of the electro-magnets of the motor, there being one set corresponding to each drum, two hand-actuators, one for each set of circuit-controlling means, clutch-mechanism arranged to connect either drum with the motor-shaft and means associated with one of the hand-actuators at the sending-station for controlling said clutch-mechanism substantially as described. 9. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft one for each number on said drum, two sets of circuit-controlling means at the sending-station for the circuits of the electro-magnets of the motor, there being one set corresponding to each drum two hand-actuators, one for each set of circuit-controlling means, clutch-mechanism arranged to connect either drum with the motor-shaft, a spring to hold said clutch-mechanism in engagement with one of the drums to return it to such engaging position when moved out of engagement

therewith, and actuating means to move said clutch-mechanism out of engagement with one number-drum and into engagement with the other number-drum, and means associated with one of the hand-actuators by which to control the operation of said actuating-means for the clutch-mechanism, substantially as described.

9. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft, one for each number on said drum, two sets of circuit-controlling means at the sending-station for the circuits of the electro-magnets of the motor, there being one set corresponding to each drum, two hand-actuators, one for each set of circuit-controlling means, yielding clutch-mechanism arranged to connect either drum with the motor-shaft permitting independent movement of the shaft with respect to the drums, and means arranged to control the operation of said yielding clutch-mechanism, substantially as described.

10. An apparatus for sending and receiving information comprising a register at the receiving-station having two rotatable number-drums, a motor having a shaft and comprising a plurality of electro-magnets and an armature common to all said magnets, two sets of circuit-selecting means for the circuits of said electro-magnets, there being one set corresponding to each number-drum, actuators arranged to operate said circuit-selecting-means, clutch-mechanism arranged between said number-drums to engage either drum and connect it with the motor-shaft and to occupy an intermediate position permitting independent movement of said shaft, and means arranged to control the operation of said clutch-mechanism, substantially as described.

11. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft, one for each number on said drums, two sets of circuit-controlling means at the sending-station for the circuits of the electro-magnets of the motor, there being one set corresponding to each drum, two hand-actuators, one for each set of circuit-controlling means, clutch-mechanism arranged between said number-drums to connect either drum with the motor shaft and to occupy an intermediate position permitting independent movement of the shaft, and means arranged to control the

operation of said clutch-mechanism, substantially as described.

12. An apparatus for sending and receiving information comprising a register at the receiving-station having two rotatable number-drums, a motor having a shaft and comprising a plurality of electro-magnets, and an armature common to all said magnets, two sets of circuit-selecting means for the circuits of said electro-magnets, there being one set corresponding to each number-drum, actuators arranged to operate said circuit-selecting means, clutch-mechanism arranged to connect either number-drum with the motor-shaft, a relay to operate said clutch-mechanism, and means arranged at the sending-station to operate said relay, substantially as described.

13. An apparatus for sending and receiving information comprising a register at the receiving-station having two rotatable number-drums, a driving-shaft for said drums, a motor having a shaft connected with said driving-shaft and arranged for rotation in either direction and comprising a plurality of separately energizable electro-magnets controlling rotation of the shaft, one for each number on the drum, clutch-mechanism for separately connecting said number-drums with said driving-shaft, a relay to operate said clutch-mechanism, two sets of circuit-controlling means at a sending-station for said motor, there being one set for each number-drum and actuators therefor, and circuit-controlling means for the clutch-operating relay associated with one of said actuators, substantially as described.

14. An apparatus for sending and receiving information comprising a register at the receiving-station having two rotatable number-drums, a driving-shaft for said drums arranged for rotation in either direction, a motor having a shaft connected with said driving-shaft and arranged for rotation in either direction and comprising a plurality of separately energizable electro-magnets controlling rotation of the shaft, one for each number on the drum, clutch-mechanism normally arranged to connect one of said number-drums with said driving-shaft and movable to disconnect said number-drum and to connect the other number-drum with said shaft, two sets of circuit-controlling means at a sending-station for said motor, there being one set for each number-drum, actuators therefor, and means controlled by one of said actuators and arranged to operate the clutch-mechanism, substantially as described.

15. An apparatus for sending and receiving information comprising a register at the receiving-station having two rotatable number-drums, a driving-shaft for said drums arranged for rotation in either direction, a motor having a shaft connected with said

- driving-shaft and arranged for rotation in either direction and comprising a plurality of separately energizable electro-magnets controlling rotation of the shaft, one for 5 each number on the drum, clutch-mechanism normally arranged to connect one of said number-drums with said driving-shaft and movable to disconnect said number-drum and to connect the other number-drum with 10 said shaft, a relay to operate said clutch-mechanism, two sets of circuit-controlling means at a sending-station for said motor, there being one set for each number-drum, actuators therefor, and circuit-controlling 15 means for the circuit of said relay arranged for operation by one of said actuators, substantially as described.
16. An apparatus for sending and receiving information comprising a register at the 20 receiving-station having two rotatable number-drums, a motor having a shaft and comprising a plurality of electro-magnets, and an armature common to all said magnets, means to separately connect the number- 25 drums with the motor-shaft, locking-means for the number-drums, and two sets of circuit-selecting means arranged at the sending-station for the circuits of said electro-magnets, there being one set corresponding 30 to each number-drum, substantially as described.
17. An apparatus for sending and receiving information comprising a register at the receiving-station having two rotatable number-drums arranged for rotation in either 35 direction, a motor having a shaft arranged for rotation in either direction and comprising a plurality of electro-magnets controlling rotation of the shaft, one for each number on said drums, means to separately connect said motor-shaft with the number-drums, two sets of circuit-controlling means at a sending-station for the circuits of the 40 electro-magnets of said motor, there being one set for each number-drum, actuators therefor, and means controlled by one of said actuators arranged to operate said locking-means, substantially as described.
18. An apparatus for sending and receiving information comprising a register at the receiving-station having two rotatable number-drums, a motor comprising a plurality of electro-magnets, and an armature common to all said magnets, means to separately 45 connect the number-drums with the motor-shaft, locking-means for the number-drums normally arranged to lock one of said drums and movable to unlock said drum and to lock the other drum, a relay to operate said locking-means, two sets of circuit-selecting means at the sending-station for the circuits of said electro-magnets, there being one set corresponding to each number-drum, and actuators therefor, and means arranged at the sending-station to operate the circuit of said relay, substantially as described.
19. An apparatus for sending and receiving 50 information comprising a register at the receiving-station having two rotatable number-drums arranged for rotation in either direction, a motor having a shaft arranged for rotation in either direction and comprising a plurality of electro-magnets controlling rotation of the shaft, one for each number on said drums, means to separately connect said motor-shaft with the number-drums, locking-means for the number-drums normally arranged to lock one of said drums and movable to unlock said drum and to lock the other drum, two sets of circuit-controlling means at a sending-station for the circuit of the electro-magnets of said motor, there being one set corresponding to each number-drum, actuators therefor, and means controlled by one of said actuators arranged to operate said locking-means, substantially as described.
20. An apparatus for sending and receiving information comprising a register at the receiving-station having two rotatable number-drums arranged for rotation in either direction, a motor having a shaft arranged for rotation in either direction and comprising a plurality of electro-magnets controlling rotation of the shaft, one for each number on said drum, means to separately connect said motor-shaft with the number-drum, locking-means for the number-drums normally arranged to lock one of said drums, and movable to lock the free drum and then to unlock the drum which was previously locked, two sets of circuit-controlling means at the sending-station for the circuits of the electro-magnets of the motor, there being one set corresponding to each number-drum, actuators therefor, and means controlled by one of said actuators arranged to operate said locking-means, substantially as described.
21. An apparatus for sending and receiving information comprising a register at the receiving-station having two rotatable number-drums, a motor comprising a plurality of electro-magnets, and an armature common to all said magnets, means to separately connect the number-drums with the motor-shaft, locking-means for the number-drums normally arranged to lock one of said drums and movable to unlock said drum and to lock the other drum, a relay to operate said locking-means, two sets of circuit-selecting means at the sending-station for the circuits of said electro-magnets, there being one set corresponding to each number-drum, and actuators therefor, and means arranged at the sending-station to operate the circuit of said relay, substantially as described.
22. An apparatus for sending and receiving information comprising a register at the receiving-station having two rotatable number-drums arranged for rotation in either direction, a motor having a shaft arranged 130

for rotation in either direction and comprising a plurality of electro-magnets controlling rotation of the shaft, one for each number on said drums, means to separately 5 connect said motor-shaft with the number-drums, locking-means for the number-drums, normally arranged to lock one of said drums and movable to unlock said drum and to lock the other drum, a relay to 10 operate said locking-means, two sets of circuit-controlling means at a sending-station for said motor, there being one set corresponding to each number-drum, actuators therefor, and circuit-controlling means 15 for the circuit of the relay arranged for operation by one of said actuators, substantially as described.

23. An apparatus for sending and receiving information comprising a register at the 20 receiving-station having two rotatable number-drums, a driving-shaft for said drums arranged for rotation in either direction, a motor having a shaft connected with said driving-shaft and arranged for rotation in 25 either direction and comprising a plurality of separately energizable electro-magnets controlling rotation of the shaft, one for each number on the drum, clutch-mechanism normally arranged to connect one of said 30 number-drums with said driving-shaft and movable to disconnect said number-drum and to connect the other number-drum with said shaft, locking-means normally arranged to lock the drum which is disengaged by 35 the clutch and movable with the clutch-mechanism to unlock said drum and to lock the other drum, two sets of circuit-controlling means arranged at a sending-station for said motor, there being one 40 set corresponding to each drum, actuators therefor, and means controlled by one of said actuators and arranged to operate said clutch-mechanism and also said locking-means, substantially as described.

45. 24. An apparatus for sending and receiving information comprising a register at the receiving-station having two rotatable number-drums, a motor having a shaft and comprising a plurality of electro-magnets and 50 an armature common to all said magnets, two sets of circuit-selecting means for the circuits of said electro-magnets, there being one set corresponding to each number-drum, actuators arranged to operate said 55 circuit-selecting means, clutch-mechanism arranged to connect either number-drum with the motor-shaft, and means arranged at the sending-station to operate the clutch-mechanism, and locking-means for the number-drums arranged to engage that drum 60 which is not engaged by the clutch-mechanism, said locking-means being arranged for control at the sending-station, substantially as described.

65. 25. An apparatus for sending and receiv-

ing information comprising a register at the receiving-station having two rotatable number-drums, a motor having a shaft and comprising a plurality of electro-magnets and an armature common to all said magnets, 70 two sets of circuit-selecting means for the circuits of said electro-magnets, there being one set corresponding to each number-drum, actuators arranged to operate said circuit-selecting means, clutch-mechanism arranged 75 to connect either number-drum with the motor-shaft, and means arranged at the sending-station to operate the clutch-mechanism, and locking-means for the number-drums movable simultaneously with the 80 clutch-mechanism and arranged to engage that drum which is not engaged by the clutch-mechanism, substantially as described.

26. An apparatus for sending and receiving 85 information comprising a register at the receiving-station having two rotatable number-drums, a motor having a shaft and comprising a plurality of electro-magnets and an armature common to all said magnets, two 90 sets of circuit-selecting means for the circuits of said electro-magnets, there being one set corresponding to each number-drum, actuators arranged to operate said circuit-selecting means, clutch-mechanism arranged 95 to connect either number-drum with the motor-shaft, locking-means for the number-drum arranged to lock either number-drum which is not engaged by the clutch, thereby 100 to restrain its rotation when disconnected from the motor-shaft, and means arranged at the sending-station to simultaneously operate said clutch-mechanism and locking means, substantially as described.

27. An apparatus for sending and receiving 105 information comprising a register at the receiving-station having two rotatable number-drums, a motor having a shaft and comprising a plurality of electro-magnets and an armature common to all said magnets, 110 two sets of circuit-selecting means for the circuits of said electro-magnets, there being one set corresponding to each number-drum, actuators arranged to operate said circuit-selecting means, clutch-mechanism arranged 115 to connect either number-drum with the motor-shaft, locking-means for the number-drum arranged to lock either number-drum which is not engaged by the clutch, thereby 120 to restrain its rotation when disconnected from the motor-shaft, a relay arranged to operate both said clutch-mechanism and said locking-means, and means at the sending-station arranged to control said relay, substantially as described.

28. An apparatus for sending and receiving 125 information comprising a register at the receiving-station having a rotatable number-drum arranged for rotation in either direction, a motor having a shaft arranged for 130

- rotation in either direction to actuate the drum and comprising a plurality of electromagnets controlling rotation of the shaft, one for each number of the drum, a relay 5 associated with the sending-instrument for controlling the circuits of said motor-magnets, a relay associated with the register for controlling the circuits of the aforesaid relay, means associated with the sending-instrument for controlling the circuit of said relay at the register, and circuit-controlling means also associated with the sending-instrument for controlling the circuits of the motor-magnets, substantially as described.
- 10 29. An apparatus for sending and receiving information comprising a register at the receiving-station having a rotatable number-drum, a motor governing rotation of the drum and comprising a plurality of electromagnets, one for each number on the drum, circuit-controlling means for the motor-magnets, a hand-actuator therefor, normally restrained from rotation, and means controlled by any one of the motor-magnets 25 when energized to release the hand-actuator permitting it to be rotated to in turn operate the circuit-controlling means for the motor-magnet, substantially as described.
- 30 30. An apparatus for sending and receiving information comprising a register at the receiving-station having a rotatable number-drum, a motor governing rotation of the drum and comprising a plurality of electromagnets, one for each number on the drum, 35 circuit-controlling means at the sending-station for the circuits of said motor-magnets, and means to hold said circuits open while said circuit-controlling means is being operated, substantially as described.
- 40 31. An apparatus for sending and receiving information comprising a register at the receiving-station having a rotatable number-drum, a motor governing rotation of the drum and comprising a plurality of electromagnets, one for each number on the drum, 45 circuit-controlling means at the sending-station for the circuits of said motor-magnets, and means to hold said circuits open while said circuit-controlling means is being operated, and means for subsequently closing the motor-magnet circuit which has been selected by the circuit-controlling means, thereby to cause the motor to operate, substantially as described.
- 50 32. An apparatus for sending and receiving information comprising a register at the receiving-station having a rotatable number-drum, a motor governing rotation of the drum and comprising a plurality of electromagnets, one for each number on the drum, 55 circuit-controlling means for the motor-magnets, a hand-actuator therefor, means to hold said actuator in an abnormal position, and means to release said actuator permitting it to resume its normal position, said
- means being controlled by means arranged at the receiving-station, substantially as described.
33. An apparatus for sending and receiving information comprising a register at the receiving-station having a rotatable number-drum, a motor governing rotation of the drum and comprising a plurality of electromagnets, one for each number on the drum, 70 circuit-controlling means for the motor-magnets, a hand-actuator therefor, means to hold said actuator in an abnormal position, which is controlled by means arranged at the receiving-station, substantially as described. 80
34. An apparatus for sending and receiving information comprising a register at the receiving-station having a rotatable number-drum, a motor governing rotation of the drum and comprising a plurality of electromagnets, one for each number on the drum, 85 circuit-controlling means for the motor-magnets, a hand-actuator therefor, means to hold said actuator in an abnormal position, and means controlled by the energized 90 motor-magnet when the number-drum has been set to release said actuator permitting it to resume its normal position, substantially as described.
35. An apparatus for sending and receiving information comprising a register at the receiving station having a rotatable number-drum, a motor governing rotation of the drum and comprising a plurality of electromagnets, one for each number on the drum, 95 circuit-controlling means for the motor-magnets, a hand-actuator therefor, means to hold said actuator in an abnormal position, and means controlled by the energized 100 motor-magnet when the number-drum has been set to release said actuator permitting it to resume its normal position, and an indicator associated with said hand-actuator by which the position of the latter may be indicated, 105 substantially as described. 110
36. An apparatus for sending and receiving information comprising a register at the receiving-station having two rotatable number-drums, a motor having a shaft, a clutch-mechanism for separately connecting the 115 number-drums with said shaft, means at the sending-station arranged to control said clutch-mechanism, circuit-controlling means for the circuits of the motor-magnets, actuators therefor, means arranged to hold said 120 actuators in abnormal position, and means at the receiving-station arranged to be controlled by the clutch-mechanism to control the release of said actuators, substantially as described. 125
37. An apparatus for sending and receiving information comprising a visual indicator and operating-electromagnet therefor, a circuit-controller for the circuit of said magnet, actuating-means for said circuit-con- 130

troller, a hand-actuator, means associated with said hand-actuator rotarily movable into and out of the path of said actuating-means and operating upon a downward movement of said actuator to engage said actuating-means when in proper relative position with respect thereto, substantially as described.

In testimony whereof, I have signed my name to this specification, in the presence of 10 two subscribing witnesses.

EDWIN V. HAGMAN.
